Patent No. 2,480,259, issued August 30, 1949, to Simon J. Petersen, Miami, Fla., for an improvement in valve grinding machine or device of the power-driven, portable, hand holding type, and one of the objects of the invention is to provide an improved machine or device of this character, which will be light in construction, easy to handle, and effective and efficient in operation. Heretofore, with devices of this character, considerable difficulty has been experienced, in that in the use thereof, unless the operator pays strict attention to the work, the surface being operated upon will be ground unevenly, due, in part, to the fact that the operator does not properly shift the device, but allows it to grind too long in one area.

It is another object of the present invention to overcome these difficulties and inconveniences, and to provide an improved grinding device, or machine of this character, which will automatically shift itself from one position to another during the grinding operation, with the result that the entire surface of the work will be evenly ground.

A further object is to provide improved means whereby the shifting of the device will be effected by the torque of the actuating motor, and such shifting will in turn be controlled by the pressure exerted upon the grinding tool, by reason of its contact with the surface being operated upon, or the resistance created by the work upon the tool.

A still further object is to provide an improved portable, hand holding machine or device of this character, in which the grinding or abrading tool will be given an oscillatory movement upon the work, and also an advancing and rotary movement during such oscillatory operation.

To the attainment of these ends, and the accomplishment of other new and useful objects as will appear, the invention consists in the features of novelty in substantially the construction, combination and arrangement of the several parts, hereinafter more fully described and claimed, and shown in the accompanying drawings illustrating this invention, in which

Fig. 1 is a view, partly in side elevation and partly in section, of a device of this character, constructed in accordance with the principles of this invention.

Fig. 2 is a detail horizontal, sectional view taken on line 2-2, Fig. 3.

Fig. 3 is a view, partly in section and partly in elevation, as taken on line 3-3, Fig. 1.

Fig. 4 is a detail horizontal, sectional view, taken on line 4-4, Fig. 3.

UNITED STATES PATENT OFFICE

2,480,259

VALVE GRINDING MACHINE OR DEVICE

Simon J. Petersen, Miami, Fla., assignor to Imperial Products, Inc., Miami, Fla., a corporation of Florida

Application November 18, 1946, Serial No. 710,711

6 Claims. (Cl. 51-29)

1

This invention relates to improvements in valve grinding device or machine of the power-driven, portable, hand holding type, and one of the objects of the invention is to provide an improved machine or device of this character, which will be light in construction, easy to handle, and effective and efficient in operation. Heretofore, with devices of this character, considerable difficulty has been experienced, in that in the use thereof, unless the operator pays strict attention to the work, the surface being operated upon will be ground unevenly, due, in part, to the fact that the operator does not properly shift the device, but allows it to grind too long in one area.

It is another object of the present invention to overcome these difficulties and inconveniences, and to provide an improved grinding device, or machine of this character, which will automatically shift itself from one position to another during the grinding operation, with the result that the entire surface of the work will be evenly ground.

A further object is to provide improved means whereby the shifting of the device will be effected by the torque of the actuating motor, and such shifting will in turn be controlled by the pressure exerted upon the grinding tool, by reason of its contact with the surface being operated upon, or the resistance created by the work upon the tool.

A still further object is to provide an improved portable, hand holding machine or device of this character, in which the grinding or abrading tool will be given an oscillatory movement upon the work, and also an advancing and rotary movement during such oscillatory operation.

To the attainment of these ends, and the accomplishment of other new and useful objects as will appear, the invention consists in the features of novelty in substantially the construction, combination and arrangement of the several parts, hereinafter more fully described and claimed, and shown in the accompanying drawings illustrating this invention, in which

Fig. 1 is a view, partly in side elevation and partly in section, of a device of this character, constructed in accordance with the principles of this invention.

Fig. 2 is a detail horizontal, sectional view taken on line 2-2, Fig. 3.

Fig. 3 is a view, partly in section and partly in elevation, as taken on line 3-3, Fig. 1.

Fig. 4 is a detail horizontal, sectional view, taken on line 4-4, Fig. 3.

2

Fig. 5 is a sectional view taken on line 5-5, Fig. 3.

Fig. 6 is a detail perspective view of the pawl-carrying member.

5 Fig. 7 is a detail elevation of the pawl.

Fig. 8 is a detail assembled view of the pawl, and a portion of the ratchet mechanism.

The device consists essentially of a casing or housing 10, in which there is located a motor having a driving shaft 11. This motor is supplied by current from any suitable source, through the medium of a conductor 12, and is controlled, in its operation, by means of a suitable switch device 13. Secured to the motor casing, preferably by means of a thread connection 14, is a collar 15, which is preferably provided with an internal flange 16 substantially mid-way of its length.

Supported by the collar 15 for rotation with respect thereto, and with respect to the motor, 20 is a support, which is preferably sectional in construction, embodying the sections 17, 18, which are separably secured together, preferably by means of a threaded connection 19. The section 17 is provided with a wall 28, in which is journaled a series of shafts 21, 22, 23. To the shaft 21 is secured a gear 24 within the section 17, and this gear 24 meshes with a pinion 25 that is carried by a gear 26 on the shaft 22. To the shaft 23 is connected a pinion 27 that is carried by a gear 28, the pinion 27 meshing with the gear 26.

Carried by the motor shaft 11, is a gear or pinion 29 that meshes with the gear 28, so that when the motor shaft 11 is rotated, the desired speed of rotation will be imparted to the shaft 21, through the medium of the intermediate connecting gears. Connected to the shaft 21, is a crank 30 having a projecting pin 31. The pin 31 projects into the bifurcation or slot 32 in a crank arm 33 that is carried by a shaft 34.

40 If desired, and in order to reduce friction, and to insure easy operation between the pin 31 and the crank 33, a sleeve or roller 35 may be provided on the pin 31, which sleeve may be provided with a flange 36 to maintain the same in position.

45 All of the gear mechanism thus far described is disposed within the section 17 of the support, and all of such gear mechanism, including the cranks 30 and 33, with the exception of the gear 29 that is carried by the motor shaft, is removable with the support, as a unitary structure. The bottom section 18 of the support is provided with an extension 36 forming a bearing for the shaft 34. Within the section 18, and through which section the shaft 34 projects, ball bearings 55 37 are provided, which are spaced from each other

in a direction lengthwise of the shaft, and in which bearings the shaft is journaled. The upper bearing 37 may be held in position in any suitable manner, such as by means of a shrink fit, and is sufficiently high to form a support for the end of the shaft on which crank 33 is located. The lower bearing 37 may be held in position by means of a gland 39, which has threaded engagement 40 with the extension 36 of the section 18 of the support.

The gland 39 is preferably provided with a recess 41 for the reception of packing material, and the end of the sleeve 42 thrusts against the bearing 37 for maintaining it in position. The sleeve 42 is preferably of the split type, as at 15 43, and is provided with a circumferential collar 44, by means of which the sleeve may be held against rotation while a nut or collar 45 is being threaded upon the sleeve to clamp the latter to the shaft 34. The gland 39 preferably has threaded engagement with the extension 36.

The rotatable support embodying the sections 17 and 18 is rotatably held in position with respect to the collar 15 and the motor casing 10, in any suitable manner, and to that end the support telescopes into the collar 15 so as to abut the flange 16, and a retaining collar 46 is threaded into the collar 15, and engages under a peripheral flange 47 on the section 18, within the collar 15. This collar 46 may be held against accidental displacement by means of a spring 46a, engaging a flange on the collar, and the adjacent edge of the collar 15. The upper edge of the section 17 is provided with ratchet teeth 48, which may be formed in the upper face of the wall of the section 17, or in an annular member 49, which latter may be secured to the section 17.

Carried by the motor casing 10, is a suitable support 50 (Figs. 2 and 6), in which is mounted a dog or pawl 51 which slides in a bearing 52. This dog or pawl is controlled by a spring 53, and the pawl co-operates with the teeth 48, the teeth 48 and the nose 54 of the pawl being so disposed with respect to each other, that the support embodying the sections 17 and 18 is adapted to be rotated in one direction only with respect to the motor and the motor casing.

When the motor is operating, the shaft 11 will be rotated to rotate the gear 29, and this gear will rotate the gears 28, 27, 26, 25 and 24, thereby imparting a rotary movement to the crank 30, which is on the shaft 21. As the crank 30 rotates, the shaft 34 will be given an oscillatory movement through the medium of the pin and slot connection 31, 32 of the crank 30 with the shaft 34.

If the pressure of the tool upon the work is slight, or is not sufficient to create a substantial resistance to the oscillation of the shaft 34, the rotatable support 17-18 will not be rotated. However, if the pressure exerted by the tool upon the work, or the resistance of the work to the action of the tool, is sufficient, the motion of the shaft 34 will be resisted, and this resistance, if sufficient, will, through the medium of the cranks 33 and 30, and the gear connection with the motor shaft 11, cause the torque of the motor to rotate the support 17-18. This will result in not only an oscillatory movement of the shaft 34, but also a bodily rotation or shifting of the shaft with the rotatable support.

In order to insure that the rotation of the support 17-18 will be in a constant direction, the pawl and ratchet mechanism is provided. As soon as the pressure of the tool upon the work, or the resistance to the oscillatory action of the

shaft 34, is relieved, the support 17-18 will not be rotated, but an oscillatory movement will be given to the shaft with respect to the support. The degree of bodily rotary movement of the shaft 34, with the support 17-18, will be controlled entirely by the pressure of the tool against the work.

One form of tool is shown in Figs. 1 and 3, and embodies a substantially cup-shaped flexible member 55, having a sleeved portion 56. In order to attach this tool to the shaft, there may be provided a split sleeve 57, having a threaded portion 58. This sleeve is telescoped upon the end of the shaft, and is secured to the shaft by means of a nut or collar 59, engaging the threaded portion 58 of the split sleeve. By adjustment of the collar 59 on the threaded portion 58, the split portion of the sleeve will be caused to bind upon the shaft to secure the sleeve 57 adjustably thereto. The tool is attached to the shaft by sleeving the tubular portion 56 of the tool over the sleeve 57. This sleeve may be slotted, as at 60, for the reception of a different kind of tool, when the tool 55 is removed.

With this improved construction, the shaft 34, and the motor shaft, are in alinement, and are spaced from each other, the connecting or operating gears being disposed therebetween in a manner that they transfer the power from center line to off-center, and then back again to center line. The result is that the working or tool carrying shaft will be in direct alinement with the motor shaft, so that the device will be balanced, as the weight of the motor, gear housing, and tool carrying shaft will be in balance when the unit is set down upon the work to be performed.

While the preferred form of the invention, and also the preferred manner of driving means or effecting rotation of the support 17-18, have been herein shown and described, it is to be understood that various changes may be made in the details of construction, and in the manner of effecting such rotary motion of the support, as well as in the combination and arrangement of all of the various parts, within the scope of the claims, without departing from the spirit of this invention.

What is claimed as new is:

1. A valve grinding device comprising a motor, 50 a housing supported by said motor and mounted for rotation with respect thereto, a tool-carrying shaft supported by said housing and mounted for rotation with respect to said housing, means within said housing and connecting said shaft with said motor for imparting an oscillatory movement to said shaft, ratchet teeth around one end of said housing, a pawl supported by said motor and engaging said teeth to thereby rotate said housing intermittently in one direction when resistance to the oscillation of said shaft is encountered.

2. A valve grinding device comprising a motor, a housing mounted on said motor for rotation with respect thereto, a tool-carrying shaft mounted in said housing for rotation with respect to the housing, a plurality of parallel shafts within said housing, means connecting said motor with said plurality of shafts to rotate said shafts, a crank on one of said last named shafts, a pin 65 on said crank, a slotted arm on one end of said tool-carrying shaft, the slot in said arm receiving said pin whereby to impart an oscillatory motion to said tool-carrying shaft, ratchet teeth on one end of said housing, and a pawl on said motor 70 engaging said ratchet teeth, whereby said housing

75 engaging said ratchet teeth, whereby said housing

will be rotated intermittently in one direction upon the application of sufficient pressure on said tool-carrying shaft.

3. A valve grinding device comprising a motor, a housing mounted on said motor for rotation with respect to the motor, a tool-carrying shaft mounted for rotation in said housing and extending therebelow, crank means within said housing and connecting said shaft with said motor to impart an oscillatory motion to said shaft, and pawl and ratchet means at one end of said housing operable in response to the application of pressure to said shaft to rotate said housing intermittently in one direction.

4. A valve grinding device as defined in claim 3, said last named means including ratchet teeth on said housing and a spring actuated pawl on said motor.

5. A valve grinding device comprising a motor, a housing mounted on said motor for rotation with respect thereto, a tool-carrying shaft mounted for rotation in said housing and extending therebelow, crank means within said housing and connecting said shaft with said motor to impart an oscillatory movement to said shaft, and pawl and ratchet means between said motor

5

and one end of said housing for rotating said housing, said last named means being normally inoperative but adapted to become operative upon the application of sufficient pressure on said shaft.

6. A valve grinding device as defined in claim 5, said last named means including ratchet teeth around the upper end of said housing and a spring actuated pawl on said motor.
